UNITED STATES PATENT OFFICE.

LOUIS M. VOIVOD, OF WARREN, OHIO.

DESIGN FOR A BADGE.

Application filed November 4, 1927. Serial No. 24,002. Term of patent 7 years.

To all whom it may concern:

Be it known that I, LOUIS M. VOIVOD, a citizen of the United States of America, residing at Warren, in the county of Trumbull and State of Ohio, have invented a new, original, and ornamental Design for a Badge, of which the following is a specification, reference being had to the accompanying drawing, forming part thereof.

In the drawing:

I claim:

The ornamental design for a badge as shown.

LOUIS M. VOIVOD.
